UNITED STATES PATENT OFFICE.

WILLIAM J. J. BURCH, OF CHICAGO, ILLINOIS.

ROTATABLE GAME-TABLE.

Specification of Letters Patent.

Patented May 7, 1912.

1,025,678.

Application filed March 30, 1908. Serial No. 423,995.

To all whom it may concern:

Be it known that I, WILLIAM J. J. BURCH, a citizen of the United States, and a resident of the city of Chicago, Cook county, Illinois, have invented certain new and useful Improvements in Rotatable Game-Tables; and I do hereby declare that the following is a full, clear, and exact description of the same, reference being had to the accompanying drawings, and to the letters of reference marked thereon, which form a part of this specification.

This invention relates to improvements in game tables, and has for its main object to afford a game board adapted to be supported upon any table and revoluble thereon, to suit the convenience of the player, and so constructed that though affording a secure bearing upon the table and readily movable thereon, yet is capable of being revolved without the possibility of injury to the table or to the game board and which may be very quickly converted from a rotatable game board into a stationary game board.

It is also an object of the invention particularly to afford an exceedingly cheap, simple and durable construction adapting the board for use in playing numerous games.

The invention consists in the matters hereinafter described and more fully pointed out and defined in the appended claims.

In the drawings: Figure 1 is a top plan view of a device embodying my invention. Fig. 2 is a transverse section thereof. Fig. 3 is an enlarged detail of a goal pin.

As shown in the drawings: A indicates a table or support, which may be of any desired kind or description and may have a top of any desired shape and upon which my improved game board is adapted to rest when the board is in use. Said game board B, as shown, is substantially rectangular in form, having greater length than width, and is preferably provided with a raised rail b, surrounding the same. In the bottom of the board and opening through the under side thereof is provided a circular recess or depression in which is seated a circular friction member C, having a peripheral downwardly directed face c, and a central downwardly directed boss c', adapted to rest on the corresponding upwardly directed peripheral face c², and central bearing face c³, of a lower bearing piece C', said circular

recess or depression being deep enough to receive both the friction member C and the bearing piece C'. Said bearing piece is provided with an upwardly directed boss c⁴, 60 which engages in a socket in the boss c', adapting the board to freely rotate on the bearing piece and also adapting the bearing piece to be very quickly removed thereby 65 converting the board into use for playing games requiring a stationary board. Said bearing piece is faced on the under side with a layer of rubber, felt or any material E, adapted to frictionally engage the surface of the table and protect the same from 70 injury and of course, if desired, the board may be provided on its under side at a suitable radius with a layer E' of the same material but in a different plane from the pad E.

The top surface of the table A may be equipped in any desired manner for any desired game, the drawing showing the same equipped with rail cushions b', pockets b⁴, wickets F and goal pins D, for playing the game of croquet with squails or caroms X, though said top surface may be otherwise equipped as desired.

In use, each player may rotate the table so that each play may be made without necessitating the player assuming uncomfortable positions which adds considerably to the pleasure of the game. Further the broad bearing face of the plate C upon the stationary bearing piece C' and the relatively small frictional surface presented assures easy rotation of the board and the pad E precludes the slippage of the turn table upon the supporting table.

By forming the circular recess or depression in the underside of the game board B deep enough to receive both the friction member C and the bearing piece C' I not only provide an aid to the boss c⁴ in resisting lateral displacement of the board, but also bring the under surface of said board almost into contact with the table A, so that lateral rocking of said board will be reduced to a minimum.

In case billiards, pool or some other game is played it may be desired to have the table stationary in which case the bearing piece is removed by simply lifting the board and replacing the same upon the table in which event the pad E' protects the table A from being marred.

It is thus seen that the table is of very

simple construction and may be converted from a rotatable to a stationary table almost instantaneously as occasion may require.

5 I claim as my invention:

1. A game apparatus, comprising a board forming the playing surface and recessed centrally in its underside, a centrally apertured plate fixed centrally in and but partially filling the recess in the underside of said board, and a bearing piece adapted to also fit into said recess in said board and having a central boss adapted to detachably engage in the central recess in said plate to support said board in rotative but detachable engagement.

15 2. A game apparatus, comprising a board

forming the playing surface, a bearing piece upon which said board is rotatably but detachably mounted slightly raised 20 from the plane of support of said bearing piece, and a ring of anti-slipping material fixed to the underside of said board and encircling said bearing piece but maintained above the plane of support of said bearing piece when said board is supported thereby.

In testimony whereof I have hereunto subscribed my name in the presence of two subscribing witnesses.

WM. J. J. BURCH.
